W. Woodard
ATTORNEY.

UNITED STATES PATENT OFFICE

BENJAMIN URICH, OF MILWAUKEE, WISCONSIN

EASEL AND SUPPORT THEREFOR

Application filed March 30, 1929. Serial No. 351,386.

The invention relates to easels designed to stand upon show-cases in stores, and to display to the public in an attractive manner, the articles supported on the front of the 5 easel and offered for sale.

The invention is embodied in a very simple construction, which can be produced at a great economy in cost when compared to that of similar structures, in that the time and 10 labor required in forming and attaching the special support or leg of the easel so as to constitute a permanent part of the structure are eliminated.

In a specific embodiment, the invention 15 resides in an easel of card-board or other light material of acceptable rigidity, and a single, detachable supporting leg made of resilient but pliable wire, formed with a coil at one end, the coiled end being adapted to be 20 engaged with an edge of the easel by friction due to compressive action of the coil, and the wire leg to be bent so as to stand at a divergent angle with relation to the plane of 25 the easel, so that the latter will be supported in substantially upright position, and display be made of the merchandise carried thereon. The attachment of the detachable leg so as to support the easel is therefore effected in an exceedingly simple operation.

20 The invention further contributes to a great saving of space in packing, thus contributing to an economy in transportation and storage costs.

The coil at the top of the supporting leg is 35 also adapted to hold a price card.

The novelty of the invention will be pointed out in the appended claims.

In the accompanying drawings:

Figure 1 is a perspective view, looking from 40 one side, of my improved easel supporting leg, such supporting leg being broken away intermediate its ends to save space in the drawings.

Fig. 2 is an edge view of the upper part of 45 the improved leg.

Fig. 3 is a rear view, in perspective, of a display card or easel, illustrating the manner in which it is supported in display position by my improved easel supporting leg, and 50 showing also the utilization of the said leg

for the purpose of maintaining a price card on the easel.

Fig. 4 is an edge view of the upper part of the structure shown in Fig. 3, and illustrating more clearly the co-operation of the parts. 55

Fig. 5 shows a slight modification in the manner of engaging the leg with the easel.

In the drawings, the numeral 10 illustrates an easel of card-board or other like material, designed to stand upon a show case, or be 60 otherwise arranged so as to display to customers the light articles carried by the easel and offered for sale.

In forming the leg for the said easel, I select a piece of straight wire 11 of suitable 65 length, and provide at one end thereof a plurality of coils 12. The wire should be resilient, so as to influence the coils into contact, but pliable or flexible enough to permit its straight run to be easily bent near its coiled 70 ends, and in ordinary use maintain its bent condition.

The leg is applied to the easel by passing the upper edge of the easel between two of the coils, so as to effect only a frictional engagement of the parts, in the manner illustrated in 75 Figs. 3 and 4, and the wire 11 is then bent outwardly at a point near the coil, so as to maintain the face of the easel in an inclined but substantially upright position. As thus arranged, the easel will be sufficiently supported 80 in its position of display.

A marker or price indicating tag 13, may be inserted between the coils 12 at the top, so as 85 to inform the contemplating purchaser as to the price at which the articles displayed on the easel are to be sold.

In Fig. 5, I have illustrated a slight modification of the manner of supporting the easel. 90 In such modification, I make a transverse slit 14 through the easel, and engage the coil at the upper end of the leg with the easel by inserting the edge of the easel at one side of the slit between the coils, as before.

A great advantage residing in my construction lies in the economy of space required in packing quantities of the easels and their supports. A further great advantage lies in the economy involved in the manufacture of the support, in that no operation of attaching 95 100

the support permanently to the easel is required.

Having thus described my invention, what I claim and desire to secure by Letters Patent of the United States, is:

1. An easel for displaying articles of merchandise comprising a sheet and a supporting leg therefor, the said leg being constituted of a length of wire coiled at its upper end, with an edge of the sheet frictionally engaged between the coils, such engagement constituting the sole connection between the sheet and the supporting leg.
2. An easel for displaying articles of merchandise comprising a sheet and a supporting leg therefor, the said leg being constituted of a length of wire coiled at its upper end, with the upper edge of the sheet frictionally engaged between the coils, such engagement constituting the sole connection between the sheet and the supporting leg.

In testimony whereof, I have signed my name at Milwaukee, this 7th day of March, 1929.

25 B. URICHE.
